graphie m. b. H., Berlin, Germany, a corpora-
tion of Germany

Application March 8, 1934, Serial No. 714,651
In Germany March 8, 1933

1 Claim. (Cl. 250—36)

When a triode tube is operated in what is known as a Barkhausen-Kurz circuit arrangement ("retarding-field" scheme) the grid is impressed with a high positive potential, whereas the outer electrode is connected with a negative or slightly positive potential. The electrons accelerated by the said high grid potential and flying through the grid are retarded in the opposing field of the outer electrode for which reason this electrode has come to be called the "retarding-electrode". Supposing that a cathode is used which is operating inside the range of saturation, then it will be found that the retarding characteristic which shows the dependence of the current of the retarding electrode upon the retarding field voltage is a mirror picture of the grid characteristic being the inter-relationship between the grid current and the retarding field voltage.

This so-called Barkhausen-Kurz short wave circuit scheme may be employed for the generation, amplification, and rectification of any desired frequencies. Compared with the usual connection of tubes with a positive outer electrode (anode) and a negatively biased grid, these two electrodes, in the Barkhausen-Kurz circuit, have not only transposed or interchanged their functions as regards potentials, but it has also been suggested to impress the input voltage between the cathode and the said retarding electrode, and to connect the output circuit with the grid. But this scheme is attended with this drawback, that the internal resistance between cathode and retarding electrode is comparatively low, indeed, that it has practically a value of only a few hundred ohms, and this as a result means a considerable load on the source furnishing the control potential.

The present invention is based upon the idea of increasing the inner tube resistance which is in parallel relation with respect to the input circuit by connecting two Barkhausen-Kurz short wave tubes in series. As a consequence, the internal resistance is doubled, while the load of the source of the control voltage is reduced one half.

A better understanding of the invention may be had by referring to the following detailed description, which is accompanied by drawing 50 wherein:

Fig. 1 shows a fundamental circuit arrangement in accordance with the present invention;

Figs. 2 and 3 illustrate, by way of example, two different forms of electron tubes having a plurality of anodes with a common grid and cathode for effecting the object of the invention;

Fig. 4 illustrates a further form of electron tube wherein shields are provided between two cylindrical anode sections to prevent interaction

between electron streams within the different sections respectively;

Fig. 5 shows a modification of the shielding arrangement of Fig. 4 where, in this case, semi-cylindrical anode segments are employed and where the shields themselves are disposed in a plane which intersects the axis of the cathode and lies in the gaps between the anode segments;

Fig. 6 shows a combination of the shielding arrangement of Fig. 5 with a capacitive collar 10 arrangement externally of the tube envelope for varying the effective inter-electrode capacity; and

Fig. 7 shows in cross section a variation in the capacitive collar arrangement as compared with 15 that of Fig. 6.

For this purpose, recourse may be had to two Barkhausen-Kurz tubes connected, e. g., in a way as shown in Figure 1. Between the two retarding electrodes is the oscillation circuit LC 20 to the midpoint of which is supplied the retarding-electrode potential E_b . The two grids are connected in parallel and are united with the source of grid voltage E_g . A circuit arrangement of this kind is serviceable both for the generation as well as the reception of ultra short waves. The two retarding electrodes work in phase opposition (push-pull), and they determine the phase of the potential variations on the electrodes in the two tubes. In the case of a wave 25 generator, the energy is delivered by the coupling of an antenna or an energy feed lead in the retarding-electrode circuit. If the arrangement is to be used for receiving, the retarding-electrode voltage must be so adjusted that the working point comes to lie about the knee of the "retarding" characteristic.

It is among the features of this invention that whether the circuit is to be used as a detector, as an amplifier, or otherwise, the tube characteristics are to be adjusted in such manner that the anode current versus anode voltage graph forms a mirror picture of the graph constituting the grid current versus anode voltage. When the adjustment has been suitably made it is found that the space current, as measured by the number of electrons emitted from the cathode, is maintained constant, while the anode current is varied inversely as the grid current. It is to be understood, however, that when operating a tube in this manner the operating range is kept within suitable limits of saturation. The tube when used as a detector is thus enabled to produce rectification in the grid circuit when radio frequency components are applied in a push-pull manner to the anodes or retarding electrodes.

As a further development of the said basic idea of the invention a special form of electron tube is here suggested which is characterized by a joint 60

cathode and a joint grid, but two or more retarding electrodes or anodes. However, in order that such a tube may be rendered useful for the present purposes, it must measure up to other requirements, and it distinguishes itself thereby from other similar tubes disclosed in the earlier art. In order that the effect of all anodes may be the same, and in order that also the length of the electron paths may be alike, it is necessary that 10 all of the retarding electrodes or anodes should be located upon the same circular or cylindrical form. In order to design a push-pull arrangement at least two retarding electrodes must be present. For the sake of insuring uniform field 15 distribution it may also be desirable, however, to provide a still greater number of retarding electrodes and to connect the same in two groups. The inter-connections between these groups are most suitably established within the vacuum vessel proper, it being understood, moreover, that 20 strict symmetry is essential for the proper function of such tubes.

The formation of the various retarding electrodes is possible in two different ways. They 25 are either formed by sections at right angles to the cylinder axis so that two or more co-axial cylinders of like diameter result (Figure 2), or else the cylinder surface is divided, by sections laid through the axis of the cylinder, into segments (Figure 3). In order that the conditions 30 of symmetry may be improved in the former case it may under certain circumstances be advisable to bring the midpoint of the cathode out of the glass bulb and to connect the two halves of the 35 cathode in parallel. Fundamentally speaking, it is not necessary that the various retarding electrodes should be of like size, though when constituting the two electrode groups this point should be borne in mind that each of the two 40 groups should have the same total surface or area. It would thus be possible, for instance, to dispose four co-axial cylinders of like length and like diameter adjacent to one another and to connect the first and the third, and the second 45 and the fourth; or else only three cylinders could be provided of which the central one has a length twice that of the two outers, with the latter two being united together.

Whether this latter arrangement comprising 50 co-axial cylinders, or the one involving segments parallel to the axis, is to be used will depend to a certain degree upon the kind of the oscillation system to be connected with the tube. Where very short waves are dealt with, say, of a length 55 below one meter, it has been found that a parallel wire system is suitable as the oscillation circuit. In this instance, segmental subdivision is particularly useful, with the retarding electrodes being then placed in the voltage loop of a parallel wire 60 system, i. e., the retarding electrodes are at high potential points on a two wire or lecher wire system, such as shown in Figs. 3 or 6.

To insure undisturbed operation of the push-pull scheme it is important that the electron 65 paths between the cathode and the two retarding electrodes (or groups thereof) should not interengage. In order to prevent this from occurring the suggestion is made according to this invention to dispose shields or screens in the space between 70 the various retarding electrodes, said shields or screens consisting preferably of metal and being kept at a constant potential. For this purpose

the shield is united, for example, with the grid or the cathode.

Figure 4 shows an exemplified embodiment of an arrangement of the said sort. K is the incandescent cathode, G the grid electrode, and B1, B2, 5 denote the two retarding electrodes having the shape of co-axial cylinders. Between these is disposed the metallic shield S which consists of a disk of circular form and which is united with the grid. 10

In Figure 5 this scheme has been applied to a tube furnished with segmental retarding electrodes. Under certain circumstances, it may be very desirable to employ a unitary metallic grid-supporting element S which of itself constitutes 15 the shielding surfaces.

The two retarding electrodes (or groups thereof) are to be regarded as the coats or plates of a condenser between which a certain potential prevails. According to another object of this invention, the said capacity is utilized for the purpose of tuning the oscillation circuit between the retarding electrodes to resonance. In order that the effective capacity may be varied, recourse is had according to this invention to an arrangement as shown in Figure 6 which has proved preferable for short wave work. The two retarding electrodes B1, B2 are located at close proximity to the inner wall of the cylindrical glass bulb Z or are made to bear directly thereon. A metallic 20 collar T is mounted on the outside of the glass envelope and its position relative to the electrodes of the tube may be adjusted by a sliding motion. The glass wall then constitutes the dielectric of two condensers, the coats or plates of which are formed, on the one hand, by the said metallic tube, and, on the other hand, by the retarding electrodes B1 and B2. It can be seen directly that the capacity of these condensers is increased, the farther the said tube T is 25 shifted over the electrodes. The structure shown in Fig. 6 also includes preferably a pair of shield plates S lying in a plane which intersects the axis 30 of the cathode and passes through the gaps between the anode segments. 35

Instead of a metal tube T, metallic coats S rotatably mounted on the glass bulb could be arranged as shown in Figure 7. If these are turned in a direction as indicated by the arrow p, the capacity between the retarding electrodes B1, B2, 50 and the coats S will be obviously altered. The number of the outer electrodes S should suitably be the same as the number of retarding electrodes B. 55

I claim:

An electron discharge device having a vacuum-tight envelope, a centrally disposed linear cathode, a cylindrically formed screen electrode completely surrounding said cathode, a plurality of anode segments having cylindrical surfaces of 60 the same radius co-axially disposed about said screen electrode, shielding means interposed between adjacent edges of said anode segments and connected to said screen electrode, an inductive circuit interconnecting said anode segments, and 65 means including a metallic collar adjustably fitted over the exterior of said envelope for capacitively tuning said inductive circuit by reaction on said anode segments through the dielectric of said envelope. 70
